Des. 184,804
Patented Apr. 7, 1959

184,804

ROTARY MOWER HOUSING

Alan D. Ellies, Columbus, Ohio, assignor to The O. M. Scott & Sons Company, Marysville, Ohio, a corporation of Ohio

Application August 8, 1957, Serial No. 47,270

Term of patent 14 years

(Cl. D40—1)

FIG. 1

FIG. 2

FIG-3

FIG-4

FIG-5

Figure 1 is a top plan view of a rotary mower housing showing my new design;

Figure 2 is a perspective view;

Figure 3 is a side elevational view;

Figure 4 is an elevational view of the right hand end of Figures 1, 2 and 3; and

Figure 5 is an elevational view of the left hand end of Figures 1, 2 and 3.

The dominant features of the design reside in the portions shown in full lines.

I claim:

The ornamental design for a rotary mower housing, substantially as shown and described.
